UNITED STATES PATENT OFFICE.

GEORGE W. STULCK, OF LOUISVILLE, KENTUCKY.

COMBINATION BABY-CRIB AND CRADLE.

1,372,105.

Specification of Letters Patent. Patented Mar. 22, 1921.

Application filed November 20, 1920. Serial No. 425,465.

To all whom it may concern:

Be it known that I, GEORGE W. STULCK, a citizen of the United States, residing at Louisville, in the county of Jefferson and State of Kentucky, have invented certain new and useful Improvements in Combination Baby-Cribs and Cradles, of which the following is a specification, reference being had to the accompanying drawings.

10 This invention relates to improvements in cribs.

An important object of the invention is to provide a device of this character which is capable of use either as a crib or cradle 15 as may be desired.

A further object of the invention is to provide in a device of this character means whereby the handling of the baby within the crib is greatly facilitated, as is also the 20 handling and changing of the bed clothes of the crib.

A further object is to provide a device of this character embodying drawers which may be employed for containing the bed 25 clothes which may be utilized on the crib and which may be moved to the open position from either side of the crib to move the contents thereof, or which may not be accidentally pushed from one side to the open 30 position at the opposite side of the crib.

A still further object is to provide in a crib of this character a concealed stairway by means of which as the child grows older he may mount to the crib unassisted, the 35 stairs of the crib being completely concealed within the device and, accordingly, not interfering with the shifting thereof from place to place.

Other objects and advantages of the invention will become apparent throughout the course of the following description.

In the accompanying drawings, wherein for the purpose of illustration is shown a preferred embodiment of my invention and 45 wherein like reference characters designate like parts throughout:

Figure 1 is a plan view of a crib constructed in accordance with my invention;

Fig. 2 is a side elevation of one side 50 thereof;

Fig. 3 is a section taken on the line 3—3 of Fig. 1;

Fig. 4 is a section taken on the line 4—4

of Fig. 2 and showing the steps in operative position in dotted lines; 55

Fig. 5 is an enlarged section taken on the line 5—5 of Fig. 3;

Fig. 6 is an enlarged fragmentary section taken on the line 6—6 of Fig. 5;

Fig. 7 is a side elevation partly in section 60 showing the manner in which the steps are supported when in operative position;

Fig. 8 is a fragmentary plan view partly 65 in section showing the mounting of the steps;

Fig. 9 is a side elevation of the stop employed for locking the crib to prevent rocking movement thereof;

Fig. 10 is a section taken on the line 10—10 of Fig. 9, and 70

Fig. 11 is a fragmentary side elevation partly in section showing the mounting of the supporting wheels in the lower ends of the counter posts.

Referring now more particularly to the 75 drawings, the numeral 10 indicates corner posts which are connected at the ends of the device adjacent their lower end by a pair of transversely spaced supports or cross bars 11 and which are connected at the upper 80 ends by a top cross bar 12. To these top cross bars is pivotally connected, as at 13, a cradle structure 14 embodying a frame work composed of upper and lower rectangular frames 15 connected by vertical up- 85 rights 16 at the corners and ends thereof.

The lower framework 15 supports the usual spring 17. To one side member of the upper framework are pivotally connected a top 18 and one complete side 19 of the 90 crib so that the top and side may be moved to open positions, in which positions they are held by the usual supporting braces 20. At the other side of the crib the vertical members 16 are connected by a transverse 95 member 21 extending longitudinally of the side of the crib approximately centrally thereof and to this transverse member is pivotally connected a door 22 which may be swung downwardly to the open position. 100 It is to be noticed that when the top is in the open position and the door 22 swung downwardly, as indicated by the dotted lines in Fig. 4, access may be readily had to the interior of the crib for rearranging the 105 clothing or attending to the child. At night

the crib may be arranged beside the bed with the side bearing the door 19 disposed toward the bed and this door moved to the position shown in dotted lines in Fig. 4, 5 the door overhanging the bed. It will be seen that when in this position the child may be readily removed and replaced without the mother or attendant moving from the bed.

10 From the foregoing it will be obvious that the crib embodies a pivotally supported receptacle for the child, which may be oscillated when desired. Means are provided for locking the receptacle against oscillation, which means are more clearly shown in Figs. 3, 9 and 10. As disclosed, the end posts are connected at the sides of the crib below the receptacle by a longitudinally extending brace member 23 to 15 which are pivotally connected the lower ends of a pair of locking members 24. These locking members each comprise a pair of spaced flat portions 25 rigidly connected to one another at one side thereof 20 by a connecting member 26. As shown in Fig. 3, the locking members may be elevated to engage the side bars of the lower rectangular frame 15 of the receptacle to prevent oscillation thereof. When not in use these 25 locking members are folded downwardly until the connecting members 26 thereof engage against the upper surface of the longitudinal supports 23, presenting when 30 in the folded position an extremely neat appearance.

A partition 27 has its ends engaged in the upper transverse supporting member 11 and its sides engage in the longitudinally extending supporting members 23. Below 40 the supports 23 and parallel thereto at each side of the crib are lower longitudinal supports 28. Extending intermediate the supports 28 and transversely of the crib structure at each end thereof, are pairs of guides 45 29 upon which are slidably mounted drawers 30, which drawers are provided centrally with a partition 31, dividing the drawer into two compartments and which drawers are provided at each end with an end member 50 or outer facing member 32, which end member 32 is provided with a latch 33, the bolt of which projects downwardly into the keeper 34 secured to the lower support 28. Each lower support is provided with a slot 55 35 alining with the bolts of the latches 33, these slots being protected by metallic sheets 36.

An inspection of Fig. 5 in connection with the foregoing will render obvious the 60 fact that by releasing the bolt at either end of the drawer from its keeper the drawer may be drawn out for the removal of its contents, but that the door may not be pushed out at the opposite side of the crib by pushing upon 65 either of the end members 32. This mount-

ing of the drawer greatly facilitates the handling of the crib and often prevents the necessity of moving from one side to the other thereof to obtain clothing for use upon the crib.

70 Formed intermediate the drawers 30 is a step compartment 37 embodying transverse members 38, each provided on the upper face thereof with an angle iron guide 39. Intermediate the transverse members 38 is 75 disposed a slide plate 40 having formed therein a groove 41 closed at one end with which coacts the enlarged head 42 which is pivotally connected to the flight of steps 43 adjacent the upper end thereof. This 80 flight of steps is composed of angle iron side members 44 having secured thereto step supports 45 of any desired construction, which supports form an attaching medium for the treads 46 of the steps. The 85 upper ends of the angle irons 44 are formed with hook portions 47 for coaction with notches 48 formed in the partition member 27 to permit the angular portions to engage against the side member 23, and the 90 lower ends of the angle iron supports are provided with caster wheels 49. The ends of the compartment are provided with doors 50, one of which has an angular portion 51 formed on its inner face 95 which is connected solidly to the crib construction by means of a pair of connecting links 52. When the door is opened, these links limit the pivotal movement thereof and when the steps are slid outwardly, and 100 shifted about their pivot, the under faces of the angle irons engage against the angular portions 51 of the doors 50 and are supported thereby. The pivotal movement of the steps likewise brings the angular portions 47 of the angle irons 44 into engagement with the side member 23, as hereinbefore set forth. The other door 50 provides an opening permitting insertion and 105 removal of steps when desired.

110 The end posts 10 are preferably provided at their lower ends with caster wheels 53 of any desired construction. In the present instance, I have shown the stirrups 54 of the wheels as being secured upon the ends of vertical bolts 55 mounted in the lower ends of the post 10. The upper ends of the bolts 55 extend into a cavity 56 formed in the post above the lower end thereof and extending through one side of the post in order that a retaining nut 57 may be applied to the bolt 55. A pivotally mounted plate 58 normally covers the outer ends of the cavities 56.

120 From the foregoing it will be obvious that I have constructed a crib which is simple 125 in construction and in operation and which greatly facilitates the attendance and care of the child; and it will likewise be obvious that the construction of the same as hereinbefore set forth is capable of some change

without departing from the spirit of my invention. I, accordingly, do not limit myself to the specific structure as hereinbefore set forth, except as so limited by the subjoined claims.

5. What I claim is:—

1. In a baby crib, end members, a receptacle supported thereby, vertically spaced longitudinally extending supports connecting the end members beneath said receptacle, transverse members mounted upon the lowermost of said longitudinally extending supports and forming drawer guides, drawers slidably mounted within said guides and extending to the opposite sides of the crib structure, said drawers being provided at each end thereof with a latch, keepers carried by said lower longitudinally extending brace members with which the bolts of said latches engage, and slots formed in said braces and alining with said bolts.
10. 2. In a baby crib, end members, a receptacle supported thereby, a storage compartment formed beneath the receptacle and extending transversely of the crib, said storage compartment being provided at one end thereof with a pivotal door, a flight of steps mounted within said compartment and having interlocking and pivotal engagement therewith whereby said steps may be shifted through the opening normally closed by said door and swung to engage one end thereof with the floor and means limiting

the pivotal movement of said door whereby said door engages the steps when the steps are in engagement with the floor, to support the upper end thereof.

3. In a baby crib, a compartment, a slide formed within the compartment, a member having interlocking engagement with the slide and a flight of steps pivotally connected with said member, said steps being provided in the upper end thereof with hook portions and a socket formed in said compartment with which said hook portions engage when the steps are swung about the pivot thereof.

4. In a baby crib, a compartment, a slide formed within the compartment, a member having interlocking engagement with the slide, a flight of steps pivotally connected with said member, said steps being provided in the upper end thereof with hook portions, said compartment having a socket formed therein in which said hook portions engage when the steps are swung about the pivot thereof to the operative position, a pivoted door for closing said compartment, and means limiting the pivotal movement of said door whereby said door engages the steps when in the operative position to support the same.

5. In testimony whereof I hereunto affix my signature.

GEORGE W. STULCK.
